Attorney

UNITED STATES PATENT OFFICE.

REXFORD C. GLOVER, OF FLINT, MICHIGAN.

MUFFLER.

Application filed September 18, 1925. Serial No. 57,154.

It is the object of the invention to provide a muffler particularly for use in automobile engines which will be of simple, sturdy construction, capable of being easily assembled and manufactured, and at the same time efficient in dissipating the energy of the discharged gases.

In the preferred design but a single path is provided for the passage of the combustion products in their travel through the muffler. Specifically, the muffler preferably comprises a casing divided into a plurality of superposed chambers, the exhaust gases passing successively from one chamber to the other in a tortuous path and in so doing giving up a large proportion of their energy prior to discharge. These chambers may, if desired, be of increasing capacity, and expansion chambers may be provided at the entrance end and at the discharge end of the muffler for further assisting in the dissipation of the energy of the gases.

In the muffler which embodies the general features of design above indicated, I have embodied a number of novel details of construction and these, as well as the broad features of novelty previously pointed out, will be described in connection with the accompanying drawing and covered by the appended claims.

In the drawing:

Figure 1 is a longitudinal sectional view through my improved muffler taken on line 1—1 of Figure 2;

Figure 2 is a section on line 2—2 of Figure 1; and

Figure 3 is a section on line 3—3 of Figure 1.

The reference character 2 indicates a tubular casing which may be of any preferred cross sectional shape. I have shown it as cylindrical. In the casing and adjacent the ends thereof are mounted heads numbered 4 and 6, respectively. These heads are provided with inwardly projecting bosses 8 and 10, upon which is telescopically received a flattened tubular member 12, the bosses 8 and 10 conforming in shape to the cross section of the member 12. The tubular member 12 divides the casing into a lower chamber 13, an intermediate chamber 15, constituted by the interior of the member 12 and an upper chamber 117. The sides 14 and 16 of the bosses 8 and 10, respectively, which lie adjacent the casing 2, are preferably provided with pressed in channel portions 17 and 19

to receive an inturned seam 20 uniting the meeting edges of the tubular member 12. By this construction the seam is confined between the casing 2 and the bosses and separation at the seam is prevented.

At the extreme ends of the casing 2 are provided heads 22 and 24 forming with the heads 4 and 6 and the casing member 2 expansion chambers 26 and 27. The head 22 has an integral extension 28 to which the conduit leading from the engine is adapted to be connected. The head 24 has a discharge pipe 30 connected to it as shown, preferably by welding.

The exhaust gases enter the expansion chamber 26 through the inlet 28, pass through an opening 32 provided in the lower portion of the head 4 into the lower chamber 13, travel the length thereof and pass through apertures 34 provided in the lower side of the flattened tubular member 12 entering the intermediate chamber 15. The gases then traverse the length of the intermediate chamber 15 and pass into the upper chamber 117 through apertures 36, these apertures being in staggered or non-alining relation with the apertures 34 to cause the gases to follow a tortuous path described. Travelling the length of the upper chamber 117 the gases are discharged through apertures 38 into expansion chamber 27 from which they are discharged into the atmosphere through conduit 30. In their travel through the casing the energy of the gases is effectively dissipated.

The manner of assembly of the parts forming the muffler is apparent from an inspection of the drawing. The parts may also be secured together in any preferred manner. I have preferred to weld the heads to the casing member 2 and I have also resorted to welding to secure the member 12 to the bosses 8 and 10.

While in the specification and claims I have referred to certain of the chambers as being upper and lower chambers it is to be understood that the designation is relative only and that the muffler may be used in reversed position if desired.

I claim:

1. In a muffler, the combination of a tubular casing having spaced heads, a tubular member extending between said heads and dividing the casing into lower, intermediate, and upper chambers, the intermediate chamber being constituted by the interior of the

- tubular member, one of the heads being apertured for the passage of exhaust gases into the lower chamber, the other head being apertured for the passage of exhaust gases 5 from the upper chamber, the tubular member being provided with staggered apertures for placing said upper and lower chambers in communication with said intermediate chamber to cause the gases to follow a tortuous path in passing through the muffler. 10
2. A muffler as defined by claim 1, the heads being provided with inwardly projecting portions cooperating with the tubular member to hold it in proper position. 15
3. In a muffler as defined by claim 1, heads in the casing beyond the first named heads and forming expansion chambers therewith, one in communication with the lower chamber and the other in communication with the upper chamber, an exhaust conduit connecting the engine with the first named expansion chamber and a discharge conduit leading from the second named expansion chamber. 20
4. In a muffler, the combination of a tubular casing having spaced heads, a flattened tubular member extending between said heads and dividing the casing into lower, intermediate, and upper chambers, the intermediate chamber being constituted by the interior of the flattened tubular member, said member being provided with apertures to permit the passage of exhaust gases through said lower, intermediate, and upper chambers successively in a tortuous path prior to their discharge into the atmosphere, 25
5. A muffler as defined by claim 4, said flattened tubular member being provided with an inturned seam, parts of said inwardly pressed portions of the heads adjacent the casing wall being provided with channels 40 for receiving the inturned seam. 45
6. The combination as defined in claim 4, said casing being extended beyond the said heads, caps for closing the ends of the casing to form expansion chambers between 50 said heads and said caps, means for admitting exhaust gases to one of said expansion chambers, and means for discharging exhaust gases from the other chamber. 55
7. In a muffler, the combination of a tubular casing having spaced heads, a tubular member extending between said heads and having wall portions fitting opposite sides of the casing to divide the casing into lower, intermediate, and upper chambers, said tubular member having an inturned seam, said heads being provided with inwardly pressed bosses conforming in shape to the cross section of said tubular member and upon which the latter is telescoped, said bosses being provided with channels for receiving the said seam, said channels being formed in the portions of the bosses which contact with the said wall portions. 60 65

In testimony whereof I affix my signature.

REXFORD C. GLOVER.
